[57] CLAIM

The ornamental design for an incremental coder, as shown and described.

DESCRIPTION

FIG. 1 is a left side elevational view of an incremental coder showing my new design, the right side elevational view thereof being a mirror image;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a top, front and right side perspective view thereof.

FIG. 2

FIG. 3

FIG. 4

FIG. 5

FIG. 6
